ATTACHMENT FOR BICYCLES OR SIMILAR ARTICLES

Lester F. Pichette, Santa Barbara, Calif.

Application February 24, 1955, Serial No. 34,684

Term of patent 14 years

(Cl. D34—15)

Fig. 2.

Fig. 1.

Fig. 1 is a perspective view of an attachment for bicycles or similar articles showing my new design; and

Fig. 2 is a top plan view, thereof, to a reduced scale.

The broken lines showing the bicycle are for illustrative purposes only.

I claim:

The ornamental design for an attachment for bicycles or similar articles, as shown and described.
